(57) **CLAIM**

The ornamental design for a washing brush, as shown and described.

DESCRIPTION

FIG. 1 is an isometric view of a washing brush showing our new design.

FIG. 2 is a front elevation view thereof.

FIG. 3 is a rear elevation view thereof.

FIG. 4 is a top plan view thereof.

FIG. 5 is a bottom plan view thereof.

FIG. 6 is a left side elevation view thereof.

FIG. 7 is a right side elevation view thereof; and,

FIG. 8 is an isometric view thereof showing the brush in an alternate environment.

The broken lines showing a brushing means in FIGS. 1–8 and the slight surface on the free end of the brush head in FIGS. 1, 4, 6, and 8 illustrate environmental structure and a portion of the brush none of which form part of the claimed design.
